DESIGN FOR AN AIR FILTER

Ernest F. Koehler, Berlin, Mass.

Application January 10, 1938, Serial No. 74,170

Term of patent 14 years

To all whom it may concern:

Be it known that I, Ernest F. Koehler, a citizen of the United States, residing in Berlin, in the county of Worcester and Commonwealth of Massachusetts, have invented a new, original, and ornamental Design for Air Filters, of which the following is a specification when taken in connection with the accompanying drawing, in which

Fig. 1 is a side elevational view of an air filter embodying my new design.

Fig. 2 is a perspective view of the air filter shown in Fig. 1, and

Fig. 3 is an end view of the air filter shown in Fig. 1.

I claim:

The ornamental design for an air filter, substantially as shown.

ERNEST F. KOEHLER.
